UNITED STATES PATENT OFFICE.

HARRY S. HART, OF CHICAGO, ILLINOIS, ASSIGNOR TO RODGER BALLAST CAR COMPANY, OF CHICAGO, ILLINOIS, A CORPORATION OF MAINE.

DOOR-OPERATING MECHANISM.

Application filed April 3, 1922. Serial No. 548,950.

To all whom it may concern:

Be it known that I, HARRY S. HART, a citizen of the United States, residing at Chicago, in the county of Cook and State of Illinois, have invented certain new and useful Improvements in Door-Operating Mechanism, of which the following is a specification.

The present invention relates to sockets. 10 More particularly the present invention relates to the construction of railway cars of the dumping type wherein it is required to turn a shaft to operate dump doors.

An object of the present invention is to 15 provide shaft operating means for dump doors which may be readily engaged by a wooden or other bar for operating a shaft.

A further object is to provide a shaft 20 operating member which may be located in an inconspicuous and unobtrusive position but which may be conveniently operated.

A further object is to provide a shaft 25 operating member for dump doors, said member having means for biting into a wooden or similar bar whereby slippage will be prevented.

Further objects will appear as the description proceeds.

Referring to the drawings—

30 Figure 1 is a cross sectional view of a railway car of the dumping type illustrating the applicability of the present invention;

Figure 2 is a view, on an enlarged scale, 35 of the embodiment shown in Figure 1;

Figure 3 is a view taken in the direction of the arrows 3—3 of Figure 2;

Figure 4 is a view taken in the direction 40 of the arrows 4—4 of Figure 2.

The numeral 1 indicates a railway car 45 having the sides 2—2. The numerals 3—3 indicate dump doors located at the bottom of the car cooperating with the floor portions 3'—3' of said car, which doors are adapted to swing downwardly to dump the

50 load. Said doors 3—3 are operated by mechanism connected with the longitudinally extending shaft 4, which mechanism is not illustrated herein inasmuch as it forms no part of the present invention. The longitudinally extending shaft 4 may be driven by the gear 5, which in turn is operated by the worm 6. Said worm is fast on the transversely extending shaft 7 and has motion communicated thereto by reason of rotation of said shaft 7. Said shaft 7 may be

supported by brackets 8—8 which form bearings and which are located adjacent to the sides of the car whereby turning effort applied to said shaft 7 at either end of said shaft will have a minimum distorting effect upon said shaft. 60

According to the present invention, each end of the shaft 7 is provided with a socket 9. The sockets 9—9 may be castings of steel or other material and may be cored out to provide a portion 10 for receiving an end of the shaft 7, said portion being secured to the shaft 7 by means of the pin 11. Each of the sockets 9 may be provided with a cylindrical outer portion 12 adapted to contact with a bearing 8 referred to above, by reason of which construction, finishing operations on the shaft 7 are minimized. The socket 9 is cored out to provide a lever receiving portion 13. The interior of said portion 13 may have a cross sectional contour wedge-shaped at both ends, as indicated in Figure 3, though a wide field of choice is possible in said cross sectional contour. The construction illustrated has certain advantages, however, inasmuch as it readily adapts itself for gripping a lever of wood or similar material. Teeth 14—14 are provided at both ends of the lever receiving portion 13, said teeth being located at the wedge-shaped portions thereof. 75

The lever receiving portion 13 of the socket 9 will preferably have its axis arranged at an angle other than a right angle with reference to the axis of the shaft 7, the preferred construction being clearly indicated in Figures 1 and 2. By reason of the angular relation between the lever receiving portion 13 of the socket 9 and the shaft 7, the socket 9 may be located within 80 the overall dimensions of the car, and a lever such as indicated by the numeral 15 will clear the side of said car whereby said lever may conveniently be operated. 95

By reason of the gripping ends of the portion 13 and by reason of the teeth 14—14 in said portion 13, a lever 15 of wood or similar material will be tightly gripped when pressure is applied thereto, whereby there will be no tendency to slip. This gripping effect, however, will not interfere with the ready removal of the lever, the net advantage being gained that workmen may conveniently dump the doors on a number of cars, one after another, expeditiously and 100 105 110

with a minimum of danger of having the levers slip relative to the operating member.

One embodiment of the present invention has been described in detail. Many modifications will occur to those skilled in the art. It is intended in this patent to cover all such modifications that fall within the scope of the invention as defined by the appended claims.

10 I claim:

1. In combination, an operating shaft for the dump doors of a railway car, a socket secured thereto, said socket having a lever receiving portion, said portion having a hole therein having wedge-shaped lever gripping walls.

2. In combination, an operating shaft for the dump doors of a railway car, a socket secured thereto, said socket having a lever receiving portion, said portion having a hole therein having wedge-shaped walls, said walls being provided with teeth adapted to grip a lever.

3. A car having a door operating shaft extending transversely thereof, said shaft having a lever receiving socket secured thereto at an end thereof, a bearing member for said socket located adjacent to a side of said car, said socket having a lever receiving portion having an axis extending at an angle to the plane of the side of said car.

4. A car having a door operating shaft extending transversely thereof, said shaft having a lever receiving socket secured thereto at an end thereof, a bearing member for said socket located adjacent to a side of said car, said socket having a lever receiving portion having an axis extending at an angle to the plane of the side of said car, said lever receiving portion having converging inside walls for gripping a lever.

5. A car having a door operating shaft extending transversely thereof, said shaft having a lever receiving socket secured thereto at an end thereof, a bearing member

for said socket located adjacent to a side of said car, said socket having a lever receiving portion having an axis extending at an angle to the plane of the side of said car, 59 said lever receiving portion having converging inside walls with teeth for gripping a lever.

6. A car having a door operating shaft extending transversely thereof, said shaft 55 having a lever receiving socket secured thereto at an end thereof, said socket having a lever receiving portion having an axis extending at an angle to the plane of the side of said car.

7. A car having a door operating shaft extending transversely thereof, said shaft having a lever receiving socket secured thereto at an end thereof, said socket having a lever receiving portion having an axis 65 extending at an angle to the plane of the side of said car, said lever receiving portion having converging inside walls for gripping a lever.

8. A car having a door operating shaft 70 extending transversely thereof, said shaft having a lever receiving socket secured thereto at an end thereof, said socket having a lever receiving portion having an axis extending at an angle to the plane of the 75 side of said car, said lever receiving portion having converging inside walls with teeth for gripping a lever.

9. A door operating mechanism for railway cars, comprising a shaft, a socket 80 mounted on the end of the shaft, said socket being adapted to receive at either end a lever and being provided with lever gripping means.

10. A door operating mechanism for rail- 85 way cars, a shaft, a lever receiving a socket mounted on the end of the shaft, said socket extending at an angle to a vertical plane passing normal to the shaft.

Signed at Chicago, Illinois, this 31st day 90 of March, 1922.

HARRY S. HART.
